The ornamental design for a display device component, as shown and described.

DESCRIPTION

FIG. 1 is a front perspective view of a wearable display device showing our design in a first configuration;

FIG. 2 is a right side elevation view of the display device component of FIG. 1;

FIG. 3 is a front perspective view of the display device component of FIG. 1 in a second configuration;

FIG. 4 is a right side elevation view of the display device component of FIG. 3;

FIG. 5 is a front perspective view of the display device component of FIG. 1 in a third configuration;

FIG. 6 is a right side elevation view of the display device component of FIG. 5;

FIG. 7 is a front perspective view of the display device component of FIG. 1 in a fourth configuration; and,

FIG. 8 is a right side elevation view of the display device component of FIG. 7.

Broken lines are environmental only and form no part of the claimed design.
